TIT. 7.

INVENTOR:

Ernest R. Simons

BY David E. Carlsen

ATTORNEY.

UNITED STATES PATENT OFFICE.

ERNEST R. SIMONS, OF ST. PAUL, MINNESOTA.

QUILTING FRAME.

Application filed September 1, 1926. Serial No. 132,967.

My invention relates to quilting frames and the object is to provide a simple, efficient and inexpensive device particularly useful as a quilting frame but also useful for a number of other purposes such as the tacking of comforters and quilting of quilts and embroidering of bed-spreads.

In the accompanying drawings:

Fig. 1 is a top or plan view of one end of my improved quilting frame.

Fig. 2 is an end elevation of Fig. 1.

Fig. 3 is a side elevation of the device.

Fig. 4 is an enlarged top view of one end of my device with some additional parts.

Fig. 5 is an enlarged sectional detail as on line 5-5 in Fig. 4.

Fig. 6 is an inside elevation of one of the end stands of my device including a collapsible work table.

Fig. 7 is a bottom view of one of the table sections 35-36.

Referring to the drawings by reference numerals, the main frame of my device comprises a pair of vertically disposed end stands connected by a horizontal bar 10. Each end stand comprises two diagonally crossed legs 11 the lower ends of which support the entire device on a floor 12 and their upper ends are fixed in the lower edge of a horizontal top bar 13. The end stand parts are preferably made of wood and connected by the previously mentioned bar 10, the latter preferably a light tube or pipe threaded at both ends, and said threaded parts being inserted one in the crossing of each pair of legs 11. 14 are threaded flange washers adjustable to engage the legs 11 at each side and thus clamp the legs rigidly between them and making the entire device stand solidly upon a floor.

It will be readily understood that the main supporting frame resembles an elongated saw-buck the end frames of which each carry a fixed horizontal bar.

15 are two rollers mounted preferably equi-distant from and parallel to the bar 10, the ends of said rollers having stub shafts 16 journaled each in the end part of a bar 13 and protruding through said bar. On the said protruding part one on both stub shafts on each roller 15 may have keyed to it a ratchet wheel 17 each such wheel adapted to be engaged by a pawl 18 pivotally fixed at 19 adjacent each ratchet. On either or both rollers 15 I secure, as at 20 in Fig. 1, one

edge of a long strip of strong fabric 21 such as canvas and adjacent the free longitudinal edge of said strip a quilt, sheet, curtain or other flat piece 22 (see Fig. 1) to be worked on, is pinned as at 23 to the piece 22 and the latter is then rolled about the roller 15 until its opposite edge is in position to be pinned to the corresponding strip 21 on the opposite roller 15. It will be readily understood that any flat piece thus secured can be stretched between both rollers and wound more or less upon either of them as desired and that the pawls 18 engage the ratchets 17 in opposite directions and the rollers may thus be held in such relation to each other that any part or desired area of the piece 22 may be stretched between them. For example, a quilt on which it is desired to embroider or otherwise apply designs, may be held taut between the two rollers and any part of its stretched area is readily accessible from both sides of the device and several persons may work on it simultaneously.

Fig. 4 illustrates auxiliary stretching device adapter to engage and stretch that part of an article 21 adjacent the end stands to pull said parts taut in a direction transversely of the stretching action of the rollers 15. This auxiliary device comprises a roller 25 mounted rotatably and parallel to the inner side of each bar 13 in brackets 26 secured at 27. Each roller carries a ratchet wheel 28 adjacent a bracket 26 and on the latter is fixed pivotally, at 29a, a pawl 29 to engage said ratchet. 30 are suitable strong cords each secured to the roller 25 with one end and its other end secured at 30a to a horizontal bar 31 arranged parallel to the roller 25 and adjustable with relation to the latter by turning the roller and manipulating of ratchet 28 and its pawl, the rollers 25 thus being utilized as winding drums. One edge of bar 31 is provided with a series of hooks 32 preferably made with sharp points adapted to engage the adjacent edge of an article 22. Thus with this auxiliary device in each end of my quilting frame stretching a quilt or other article endwise and the rollers 15 adapted to stretch the article transversely, such article can be stretched four ways simultaneously.

In the modification shown in Fig. 6 the end stands are provided each with a central depending board 33 in a common plane with the inner side of board 13, said board 33

extending downwardly below the bar 10. 34 are two parallel grooves in the board extending upwardly and continuing on the inner side of the board or bar 13 to a point near 5 the top edge of the latter where each groove communicates with a horizontal groove 34^A having downward extensions or pockets 34^B. 35 are two table boards made each of suitable thin boards and made rigid by two 10 end cleats 36 and intervening cleats 36^A for bracing. Each board has two outwardly extending pins 37 suitably fixed at corresponding inner ends of the cleats 36. These pins 37 in each board are slidably engaged in 15 corresponding grooves 34 of the opposite end frames and normally rest in the bottoms of said grooves with the board 35 extending upwardly and outwardly as in Fig. 6 with the upper part of each cleat 36 resting 20 against a pin 38 fixed in bar 13 inwardly of each roller 15. It is obvious that the boards 35 may be raised to a horizontal plane by sliding their lower ends up to the transverse grooves 34^A and guiding the pins 37 to 25 rest in either of the pockets 34^B. With the pins 37 in the latter position the boards are on a common horizontal plane, as shown dotted in Fig. 6, with the cleats 36-36^A supporting them on the rollers 15. The table 30 thus provided may be used for various purposes such as preparing quilts, comforters, or any articles before or independently of placing same on the stretching device. This modified construction is of course possible 35 to install in the form of my device having the end rollers 25, in which case the said roll-

ers may be mounted on the outer sides of the bars 13 (not shown).

The use of my quilting frame has been fully disclosed in the foregoing specifi- 40

What I claim is:

A quilting frame comprising two vertically disposed end stands and a horizontal frame bar connecting said end stands, 45 rollers rotatably mounted between said end stands in a common horizontal plane above said frame bars, means for detachably securing a quilt to the said rollers and for holding a portion of it taut between said rollers, a collapsible table member between said end frames and comprising two corresponding sections adapted to be laid in a common horizontal plane upon said rollers and means 50 for retaining the adjacent edges of said sections in said horizontal plane, said latter means comprising a fixed pin projecting endwise from each of the inner corner parts of said tables; a vertical guide board extending vertically and downwardly from the upper central part of each end frame or stand and said board and end stand being provided with parallel vertical grooves each of which is slidably engaged by one of said pins, and said grooves communicating each 55 with a horizontal groove at the upper end of the vertical groove and said horizontal groove having downwardly directed pockets for the purpose described.

In testimony whereof I affix my signature.

ERNEST R. SIMONS.
